D. B. DISS & O. E. HAMILTIL,
GREASE CUP,
APPLICATION FILED JAN. 12, 1917.

1,247,235.

Patented Nov. 20, 1917.

UNITED STATES PATENT OFFICE.

DANIEL B. DISS, OF NEWARK, AND OTTO E. HAMTIL, OF RAHWAY, NEW JERSEY,
ASSIGNORS TO THE BURNS & BASSICK COMPANY, OF BRIDGEPORT, CONNECTICUT,
A CORPORATION OF CONNECTICUT.

GREASE-CUP.

1,247,235.

Patented Nov. 20, 1917.

Application filed January 12, 1917. Serial No. 142,001.

To all whom it may concern:

Be it known that we, DANIEL B. DISS and OTTO E. HAMTIL, both citizens of the United States, and residing, respectively, at Newark, Essex county, New Jersey, and Rahway, Union county, New Jersey, have invented certain new and useful Improvements in Grease-Cups; and we do declare the following to be a full, clear, and exact 10 description of the invention, such as will enable others skilled in the art to which it appertains to make and use the same.

This invention relates to certain new and useful improvements in a grease cup and 15 the method of making the same, and pertains more particularly to an improvement on the cup shown in Letters Patent No. 1,088,770, dated March 3, 1914.

In the patent above noted, it was an aim 20 to provide a frictional contact between the body and the screw threaded cap to prevent accidental retrograde movement of the latter, that is, the cap could be turned manually in either direction but with difficulty 25 through the resistance afforded by a leather disk carried by the body in the path of the screw threads of the cap.

The present invention has for the primary 30 object to simplify the cup construction and improve the method of mounting the leather disk thereon.

In the drawing;

Figure 1 is a vertical section of the improved grease cup;

Fig. 2 is a transverse section on line 2—2 of Fig. 1, the cap being removed;

Fig. 3 is a fragmentary vertical section of the cup body showing the leather disk in position ready to be clamped; and

Fig. 4 is a view similar to Fig. 2 in which the disk securing lip or spur is corrugated or pressed into the leather disk.

The grease cup is of the force feed type and comprises a body 1 having its top flange 45 externally screw threaded, as at 2 to receive the screw threads 3 of the cap 4 whereby on turning down the latter the lubricant will be expressed through the discharge end 5 of the cup body in an obvious manner.

50 In the present instance, the body is drawn up from a single piece of sheet metal and immediately below its top flange has a lip or spur 6 thrown up, as is clearly depicted

in Fig. 3. This spur is preferably thrown up in cylindrical form to facilitate the positioning of the leather disk 7 thereabout, after which said spur is spun or curled outwardly and backwardly upon the body to clamp or clench the disk in place (Fig. 1).

The fibrous disk washer is of a diameter 60 to extend in the path of and engage the cap threads 3 to afford frictional resistance sufficient to eliminate retrograde turning of the cap. The periphery of the disk is smooth and, of course, the cap threads will 65 score therein when screwed down.

In instances where the inner periphery of the disk is circular, the clamping spur may be corrugated or otherwise pressed into the disk, as at 8, to retain the same from rotation.

70 It will thus be noted that the body and disk securing means is a simple and integral structure which fact renders the cup of an exceedingly practical nature, since previous 75 constructions embodied a plurality of parts which were difficult to assemble and costly in production.

The herein-described method and construction equips the grease cup body with a disk 80 securing means without the addition of a single part, the whole being drawn from a single piece of sheet metal. It is therefore obvious that the present cup may expeditiously be manufactured with no parts to 85 wear loose or become dislodged.

The washer is thus applied by merely slipping same over the end 5 of the cup and since the external contour of the lip conforms to that of the internal circumference 90 of the washer, the latter is slid over lip 6 without cutting the washer. In other words the washer is applied in its integral form and without splitting same.

95 What is claimed is:

1. The herein-described method of securing washers intact to grease cups and without cutting of the washers, which consists in providing a bendable lip on the cup of an external form substantially corresponding 100 to the internal circumference of the washer, then in sliding the washer over the lip and finally in bending the lip to engage beneath the washer to hold the latter in place.

2. The herein-described method of securing washers intact to grease cups and with-

out cutting of the washers, which consists in displacing a part of the cup to form a substantially annular lip which latter has a free end part facing toward an end of the cup and has a peripheral part substantially parallel to the longitudinal axis of the cup and of a diameter substantially equal to the internal diameter of the washer, then in sliding the washer over the periphery of the

lip, and finally in forcing the free end part 10 of the lip up against the washer.

In testimony whereof we affix our signatures in presence of two witnesses.

DANIEL B. DISS.
OTTO E. HAMTIL.
